UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A HAND SUPPORTED THERAPEUTIC LIGHT

Application filed February 19, 1932. Serial No. 42,933. Term of patent 14 years.

To all whom it may concern:

Be it known that I, WILLIS O. PROUTY, a citizen of the United States, and a resident of the city of Hermosa Beach, county of Los Angeles, and State of California, have invented a new, original, and ornamental Design for a Hand Supported Therapeutic Light, of which the following is a specification, reference being had to the accompanying drawing, forming part thereof, in which:

Figure 1 is a side elevation of a light embodying my invention:

Fig. 2 is an end elevation thereof; and
Fig. 3 is a bottom plan view thereof.

The dominant features of the design are the configuration of the casing for accommodating the radiant element, and the handle of the casing.

I claim:

The ornamental design for a hand-supported therapeutic light substantially as shown and described.

WILLIS O. PROUTY.
